BOXMAKING MACHINE

William B. Leavens, Jr., West Orange, N.J.

Application October 22, 1949, Serial No. 123,049

18 Claims. (Cl. 93—44)

1

This invention relates to box making machinery, and the invention has reference, more particularly, to mechanism for producing boxes by forming box blanks of sheet material about continuously moving form blocks; said mechanism including means for successively delivering box blanks for application to and reception by successive form blocks, and further including means for discharging boxes, formed from the box blanks, from the continuously moving form blocks.

An object of this invention is to provide, in a box making machine, a multiplicity of form blocks so pivotally interconnected one with another as to provide an endless chain thereof adapted to be moved continuously through a predetermined circulatory path defined by straight outgoing and return courses connected by curved end courses; the interconnected relation of said form blocks being such that adjacent form blocks close together in box material gripping relation, as they enter and move through the straight courses of their circulatory path of movement, but which separate, as they move through a curved end course of said circulatory path of movement, so that the form blocks are individually presented for application thereto of box blanks to be formed thereon, and so that completed boxes can be discharged from individual form blocks while the latter are thus separated.

Another object of this invention is to provide, in combination with an endless chain of form blocks of the kind above mentioned, novel means for automatically removing box blanks successively from a supply thereof, spreading the removed box blanks, and then carrying the spread box blanks into the path of movement of separated form blocks, whereby the spread box blank will be taken up by the latter so as to be operatively mounted thereon, and thereafter carried by said form blocks subject to box forming manipulation thereof.

A still further object of this invention is to provide means, adjacent the outgoing straight course of the moving chain of form blocks, adapted to manipulate and secure box end forming portions of the box blanks, whereby to complete folding of the box blanks about the moving form blocks into finished boxes.

The invention has for another object to provide controlled and timed means for automatically removing completed boxes from the form blocks while the latter moved in separated relation to their adjacent fellows.

Other objects of this invention, not at this time

2

more particularly enumerated, will be understood from the following detailed description of the same.

An illustrative embodiment of this invention is shown in the accompanying drawings, in which:

Fig. 1 is a plan view of a box making machine according to this invention; Fig. 2 is a longitudinal sectional view thereof, taken on line 2—2 in Fig. 1; Fig. 3 is a transverse vertical sectional view, taken on line 3—3 in Fig. 1; Fig. 4 is another transverse vertical sectional view, taken on line 4—4 in Fig. 1; Fig. 5 is also a transverse sectional view, taken on line 5—5 in Fig. 1; and Fig. 6 is another transverse vertical sectional view taken on line 6—6 in Fig. 1.

Fig. 7 is a detail fragmentary cross sectional view, taken on line 7—7 in Fig. 2.

Fig. 8 is a detail horizontal sectional view, taken on line 8—8 in Fig. 3.

Fig. 9 is a cross sectional view through a single form block of the endless chain thereof, this view being drawn on an enlarged scale.

Fig. 10 is a plan view of a box blank adapted to be worked by the illustrative form of the machine of this invention.

Similar characters of reference are employed in the hereinabove described views, to indicate corresponding parts.

In the machine of this invention, a multiplicity of form blocks 11 are interconnected so as to provide an endless chain thereof. The form blocks 11 provide molds or forms about which box blanks can be folded into a desired box formation, and said form blocks are sized in length, width and height to correspond to the dimensions of the box formation to be formed thereon.

Each form block 11 is provided, intermediate its ends and in laterally offset downward extension from its sides, with perforate hinging tongues 12. Said hinging tongues 12 are so disposed that, when the form blocks 11 are arranged side by side, the hinging tongues 12 at one side of one form block will lap corresponding hinging tongues 12 at the opposed side of an adjacent form block, with the perforations 13 of the thus lapped hinging tongues in alignment for reception and extension therethrough of hinge pins 14. In this manner a desired number of form blocks 11 are pivotally interconnected in succession so as to form an endless chain thereof, wherein the form blocks are disposed with their lengths transverse to the length of the endless chain thereof. There are two sets of lapped hinging tongues 12 between adjacent form blocks, and these sets are so spaced apart as to provide paral-

lel rows thereof along the length of the endless chain assembly of the form blocks.

The endless chain assembly of form blocks 11 is mounted in the machine so as to preferably extend horizontally and lengthwise thereof, and to this end the machine is provided with suitably supported transverse shafts 15 and 16, one of which is adapted to be power driven. Fixed on the shaft 15 are sprocket wheels 17, and fixed on the shaft 16 are like sprocket wheels 18. Mounted on the hinge pins 14 of the lapped hinging tongues 12, by which the form blocks 11 are pivotally interconnected, are antifriction rollers 19 which are adapted to be engaged by the sprocket wheels 17 and 18, whereby to drive the endless chain assembly of form blocks.

As thus supported and driven, the endless chain assembly of form blocks is arranged to provide an upper outgoing straight course or run of form blocks extending from the sprocket wheels 17 to the sprocket wheels 18, and a lower return straight course or run thereof extending from the sprocket wheels 18 back to the sprocket wheels 17. As the form blocks 11 move into and along said straight courses or runs, the same will close together in closely contiguous side by side relation, so that box material disposed intermediate adjacent form blocks, thus closed together, will be gripped by and between said adjacent form blocks, as will later herein be more fully explained. As the form blocks of the endless chain assembly thereof move around the sprockets 17 and 18, adjacent form blocks will be caused to separate one from another, in the manner clearly to be understood from an inspection of Fig. 2. When thus separated, individual form blocks are segregated so as to facilitate operative application thereto of a box blank to be formed about the same.

Suitably supported by the machine framework, to extend longitudinally between the sprocket wheels 17 and 18, are track plates 20. These track plates are provided, along their top marginal portions, with upper trackways 21 upon which the rollers 19 of the endless chain assembly of form blocks ride, whereby to support the outgoing straight course or run thereof. Said track plates are further provided, along their lower marginal portions, with lower trackways 22 upon which the rollers 19 of the endless chain assembly of form blocks ride, whereby to support the return straight course or run thereof.

The machine is adapted to form boxes from box blanks which are suitably formed and scored for manipulation of their parts so as to dispose the same in desired box forming relation.

An illustrative form of box blank adapted to be manipulated by the machine operations is shown in Fig. 10, and comprises a bottom panel A, side panels B and C, end panels D extending from bottom panel A, and end flaps E which respectively extend from respective ends of the side panels B and C.

Preparatory to supplying the box blanks to the machine, subject to the box forming operations thereof, the side panels B and C are folded beneath the bottom panel A in superposed relation thereto and to each other, as shown in Fig. 2. When thus initially folded, the box blanks are stacked in a magazine, which is disposed at the receiving end of the machine. The box blanks are subject to successive withdrawal from the magazine by properly timed means which is operative to unfold and spread the side panels B and C of a withdrawn box blank, and then to

carry said box blank to a position to be engaged and taken up by a form block 11 which is separated from its fellows, and which is moving to join the upper outgoing straight course or run of the endless chain assembly of form blocks and so as to be thereby carried forward subject to box forming manipulation.

An illustrative form of box blank magazine, as shown, is aligned with and suitably spaced relative to the receiving end of the endless chain assembly of form blocks 11. This magazine comprises side walls 23 which are laterally spaced apart so as to accommodate the initially folded box blanks in longitudinal extension therebetween, when said box blanks are stacked in the magazine. Connected with the lower ends of the magazine side walls 23 are inwardly projecting tapered ledges 24 (see Fig. 3), which are engaged by the free end portions of the end panels D of the bottommost box blank, thus upwardly inclining said end panels D so that the side panels B and C with their end flaps E are unsupported, and tend to swing down somewhat from the plane of the bottom panel A so as to be slightly spaced from the latter, whereby means for withdrawing the bottommost box blank from the magazine can enter between the ends of its bottom panel A and the underlying side panels B and C, as will be subsequently explained.

From the lower end of the magazine, said tapered ledges 24, together with guide bars 25, extend toward and terminate adjacent to the receiving end of the endless chain assembly of form blocks (see Fig. 1), thus providing guides along which withdrawn box blanks may move, when transported from the magazine, and whereby the box blanks are held against longitudinal shift or displacement until operatively deposited upon a form block 11. The means for withdrawing box blanks from the magazine, and transporting the same for engagement by and deposit on a form block 11 of the endless chain assembly of form blocks, comprises mechanisms respectively supported by the machine framework adjacent to the receiving end of the endless chain assembly of form blocks, and respectively adjacent to opposite sides of the box blank supply magazine. Said mechanisms being alike in structure, description of one thereof will comprehend the other, corresponding parts of each being identified in the drawings by like reference numerals. Each said mechanism comprises a housing 26 supported by the machine framework. Mounted in the top of the housing 26 is a turntable 27 which projects through an opening 28 in the top wall 29 of said housing. Mounted on the turntable 27, in diametrically spaced apart relation, are box blank pickup carriers 30 and 31. These box blank pickup carriers are adapted to be revolved by the turntable 27, and thus caused to be advanced toward the box blank magazine so as to enter beneath the bottom panel and between the side panels of the bottommost box blank in said magazine, thereupon being operative to withdraw the thus engaged box blank from the magazine, and then carry it forward into the path of a rising individual form block 11 at the receiving end of the endless chain assembly of form blocks. To assure functioning in this manner, the pickup carriers are so controlled, as they revolve with the turntable, as to be constantly maintained parallel to the longitudinal axis of the engaged box blank.

Suitable power transmission is provided for revolving the turntable 27 and controlling the

positions of the pickup carriers as aforesaid, while the latter revolve with the turntable. Such power transmission is subject to variation in form and arrangement. An illustrative form and arrangement of such power transmission, as shown, is as follows:

Supported by a bearing 32 within the interior of the housing 26 is a perpendicular hollow shaft 33, to the upper end of which the turntable 27 is affixed. Each pickup carrier 30 and 31 is fixed upon a supporting shaft 34 therefor, said shafts 34 being journaled in the body of the turntable 27; the latter having an internal chamber 35 across which said shafts 34 extend. Extending upwardly through the hollow shaft 33 and into the chamber 35 of the turntable is a shaft 36. Fixed upon shaft 36 within the turntable chamber is a pickup carrier control gear 37 which meshes with respective pinions 38 with which the supporting shafts 34 of the pickup carriers are provided. The shaft 15 of the receiving end of the endless chain assembly of form blocks extends transversely through the housings 26, being journaled in bearings 39 with which the latter are provided. Said shaft 15 functions as a drive shaft for the turntable and pickup carrier transmissions. Shaft 15 transmits its motion through gearing 40-41 to a perpendicular lay shaft which is journaled in the housing 26. Said lay shaft 42 transmits its motion through gearing 43-44 to a countershaft 45 which is also journaled in the housing 26. The hollow shaft 33, by which the turntable 27 is revolved, is driven from said countershaft 45 by gearing 46-47, and shaft 36, by which the pickup carrier control gear 37 is rotated, is also driven from said countershaft 45 by gearing 48-49. The respective drive gearing for the turntable and for control of the pickup carriers are so relatively sized that, as the turntable 27 is revolved, the pickup carriers will be simultaneously rotated relative to the turntable in such timed relation thereto as to maintain the pickup carriers, in all positions thereof, parallel to the longitudinal axes of the box blanks upon which they operate. It will also be understood that the transmission by which the turntable is revolved is so designed as to assure properly timed in and out movements of the pickup carriers relative to the speed of movement of the endless chain assembly of form blocks.

Each pickup carrier 30 and 31 is suitably shaped to enter the ends of a bottommost box blank of a stack thereof contained in the magazine, and then to spread apart the side panels B and C of the engaged box blank while advancing the latter to a point opposed to an approaching individual form block 11, as said form block moves around the sprockets 17, in manner to be separated from its adjacent fellows, on its way to the outgoing straight course or run of the endless chain assembly of form blocks. To this end, each pickup carrier comprises a body which projects horizontally inward from its shaft supported connection with the turntable 27. The body is provided with a flat top face 50 which lies in a plane parallel to and slightly below the plane of the bottom panel A of a bottommost box blank contained in the supply magazine. The free end portion of the body is provided with a straight forward side edge 51 bordering its top face 50, which edge is parallel to the longitudinal axis of said body, and with an inclined rearward side edge 52 converging toward said straight forward side edge, thus providing a relatively narrow tapered tip portion 53. The underside 54 of the

free end portion of said body is rearwardly and downwardly inclined or undercut so that the tip portion 53 is of wedge shape in longitudinal vertical section, thus providing said tip portion with a relatively sharp leading edge. As thus shaped, the free end portion of the body is not only well adapted to enter the ends of a folded box blank lodged at the bottom of the supply magazine, but also, as it advances thereinto while withdrawing the same from said magazine, is further adapted, by engagement of the side margins of its undercut underside 54 with the side panels B and C of the box blank, to outwardly spread said side panels. The forward and rearward sides 55 and 56 of the body, which extend back from the free end portion thereof, are adapted, upon further penetration of the body into an end of an engaged box blank, to support the side panels of the box blank in said outwardly spread opened out positions (see Fig. 2). Mounted on the forward side 55 of the body is a forwardly projecting clip 57 of suitable cross-sectional shape and of suitable material, which, as the body enters an end of a box blank and spreads its side panels, will engage over the outward leading side panel B, thus firmly holding the box blank against lateral shift or displacement relative to pickup carrier, as the latter carries the same forwardly from the magazine.

As a further safeguard against accidental shifting or displacement of box blanks as they are carried from the supply magazine and deposited upon form blocks 11, a hold down means is provided for cooperation with the pickup carriers and the box blank receiving form blocks. This hold down means may be of any suitable form or kind which is adapted to exert hold down pressure upon the carried box blanks. An illustrative form of such hold down means, as shown, comprises a transverse pivot rod 58 which is disposed above and across the outgoing straight course or run of the endless chain assembly of form blocks, adjacent to the receiving end thereof, and which is supported by suitable brackets 59 extending e. g. from the track plates 20. Pivoted connected with the pivot rod 58, to extend rearwardly therefrom, is a carrier bar 60. Mounted on said carrier bar 60, so as to be suitably located between the box blank supply magazine and the receiving end of the endless chain assembly of form blocks, are a series of rollers 61 by which the box blanks on the pickup carriers, undergoing deposit on a form block 11, will be engaged and held down against upward displacement. Also mounted on said carrier bar 60, between the same and the pivot rod 58, are carrier bar supporting rollers 62 which engage the outgoing straight course or run of closed together form blocks. It will be understood that the carrier bar 60 and its rollers may be upswung out of the way in event it is desirable to gain free access to the underlying mechanisms, as e. g. to remove therefrom a defective box blank.

In the operation of the machine, when pickup carriers advance a spread box blank to a point which opposes the same to the path of a rising individual form block 11 at the receiving end of the endless chain assembly of form blocks, the relative movements of the turntable revolved pickup carriers and the rising or advancing form block 11 are so timed that the withdrawing movement of the pickup carriers will accompany the entering movement of said form block, until, by the time the form block contacts the bottom panel A of the entered box blank, the pickup

carriers will have fully withdrawn from beneath said bottom panel, and out of the path of onward movement of the form block, whereupon the box blank is operatively deposited upon said form block, and is then carried thereby to enter therewith upon the upper outgoing course or run of the endless chain assembly of form blocks.

As a box blank bearing form block 11 enters upon the upper outgoing straight course or run of the endless chain assembly of form blocks, it will close upon a preceding box blank bearing form block, so as to firmly grip or clamp the intervening side panels of the borne box blanks between the contiguous sides of the thus closed together form blocks. It will be obvious from an inspection of Fig. 2 that, as box blank bearing form blocks move along their straight courses or runs, the box blanks will not only be firmly gripped and clamped thereto against shift or displacement while end flaps and end panels of the blanks are undergoing folding and gluing operations and glue setting, but also the side panels B and C of the blanks will be immovably held in close hugging and straight or non-bulging relation to the form blocks, whereby to assure proper symmetrical folded disposition of the side flaps and end panels for gluing, and consequently a finished box of perfect rectangular symmetry.

Adjacent to respective sides of the receiving end portion of the upper outgoing straight course or run of the endless chain assembly of form blocks 11 are arranged devices for inturning or infolding the end flaps E of the form block carried box blanks, then applying glue to the end panels D of said blanks, and thereafter down-folding said end panels for adherence to the infolded end flaps E. These devices are of more or less conventional forms which, in principle, are well known to the art. As shown (see Fig. 1), these devices comprise end flap folder rails or plates 63; glue applicator rolls 64 and their glue supply reservoirs 65; and end panel turning plows 66. The glue applicator rolls 64 are mounted on drive shafts 67 which are journaled in the reservoirs 65, said shafts and rolls being driven by belt and pulley transmission means 68 from the shaft 15, or in any other suitable or convenient manner. As a form block carried box blank is moved forward into engagement with the end flap folder rails or plates 63, the leading end flaps E thereof are engaged and inturned by the latter. Mounted upon the forward sides of the pickup carriers 30 and 31 are devices for inturning the trailing end flaps E, whereby to cause the same to be engaged and held infolded by the rails or plates 63 as the box blank is moved behind the latter. These devices comprise forwardly projecting folder fingers or blades 69 which are suitably shaped and offset so that their free end portions are disposed to engage the outwardly extending trailing end flaps E of the box blank which is entering between the rails or plates 63, whereby, as the pickup carriers move forward to dispose a box blank carried thereby in position to be engaged by and deposited upon a next succeeding form block, said fingers or blades 69 will inturn the trailing end flaps E of the box blank on the preceding form block, so that the thus infolded trailing end flaps will pass behind and thereupon be held infolded by the rails or plates 63 (see Fig. 1). The end panels D of the form block carried box blank extend above and outwardly over the end flap folder rails or plates 63, and thus present their under or inner faces for glue receiving contact with the peripheries of

the glue applicator rolls 64, as the same are advanced across the latter. After receiving application of glue, said end panels D, as the form block carried box blank continues its advance, are passed in engagement with the plows 66, by which the same are down-turned across the infolded end flaps E to which said end panels are adhered by the glue, and thus secured with said end flaps in box end forming position.

Contiguous to the respective sides of the upper outgoing course or run and of the lower return course or run of the endless chain assembly of form blocks, and so as to extend between the above described box end forming devices and the outer end of the latter, are means to retain the parts of the box end formations against displacement or separation while the glue which secures the same together is setting. Here again, such retainer means may be varied in form and arrangement, but preferably comprises driven belts having their operative courses or runs opposed to the ends of the moving form blocks and boxes formed thereon as said form blocks traverse their straight courses or runs. The said retainer belts comprise upper belts 10 contiguous to respective sides of the upper outgoing course or run of the form blocks, and lower belts 11 contiguous to respective sides of the lower return course or run of the form blocks. The upper belts 10 are supported by and run between inner pulleys 72 and outer pulleys 73, and the lower belts 11 are supported by and run between inner pulleys 74 and outer pulleys 75. In a preferred arrangement, as shown, the inner pulleys 72 and 74 are idler pulleys which are rotatably mounted on carrier bracket structures 76 suitably supported in connection with the machine framework, as e. g. by attachment to outer sides of the track plates 20 (see Fig. 5). The outer pulleys 73 and 75 are drive pulleys by which the belts are actuated. The respective shafts 77 and 78 of said outer pulleys 73 and 75 are journaled in respective upper and lower bearings 79 and 80 of gear boxes or housings 81 which are suitably supported in connection with the machine framework. The shaft 16 of the outer end of the endless chain assembly of form blocks is journaled transversely through the gear boxes or housings 81, and functions as a power shaft for driving the pulleys 73 and 75 through suitable intermediate transmission means. Such transmission means, in an illustrative form thereof as shown, comprises countershafts 82 which are journaled in bearings 83 provided in the outer side walls of the gear boxes or housings 81. These countershafts are driven from the shaft 16 by gearing 84-85. Fixed on the countershafts 83 are drive pinions 86. The drive pinions 86 mesh with upper driven pinions 87 which are fixed on the shafts 77 of the upper outer pulleys 73, and also mesh with lower driven pinions 88 which are fixed on the shafts 78 of the lower outer pulleys 75. It will be obvious that, by the described transmission gearing 86-87-88, the operative courses of the upper belts 10 will be driven in directions corresponding to the outgoing movement of the upper course or run of the form blocks, while the operative courses of the lower belts 11 will be driven in directions corresponding to the ingoing or return movement of the lower course or run of the form blocks. The gearing ratios of said transmissions are such that the speeds of the belts correspond to the speed of the endless chain assembly of form blocks.

Each form block 11 is provided with means operable to remove a finished box therefrom. Means for this purpose, in an illustrative form thereof as shown, comprises a pair of kickoff levers 89 which are pivotally mounted within the form block interior to respectively extend toward the opposite ends of the form block, and so as to normally lie flush with the top thereof, subject to outswinging movement therefrom. Unitary with and extending from the inner ends of the kickoff levers 89, to project downwardly through openings in the bottom of the form block, are bell-crank arms 90. Mounted on the free ends of said bell-crank arms 90 are anti-friction rollers 91. Extending around and between the shafts 15 and 16 of the endless chain assembly of form blocks, within and concentric to the circuit of the latter, is a raceway means by which the bell-crank arms 90 of the kickoff levers 89 are controlled. Said raceway means is formed by end members 92 and 93 respectively mounted around the shafts 15 and 16. These end members are provided with laterally spaced flanges 94 which are continued by correspondingly spaced raceway side plates 95 which extend longitudinally from one to the other of said end members. The flanges 94 and raceway side plates 95 are so spaced as to be engaged and ridden respectively by the rollers 91 of the bell-crank arms of the oppositely extending kickoff levers 89 of each form block, whereby to normally hold said kickoff levers retracted within the form blocks, as the latter move around the circuit of the endless chain assembly thereof.

At a convenient location within the circuit of the raceway, means is provided for moving the bell-crank arms 90 whereby to outswing the kickoff levers 89, and by such movement of the latter, to exert outward thrust against the bottom panel A of a finished box, thereby to push or kickoff said box from the form block upon which it was shaped. The means for this purpose is preferably provided in connection with the raceway end member 92, at a point where the endless chain assembly of form blocks makes its upward turn out of the return course or run thereof. Such location permits said return course or run of the form blocks to be utilized so as to provide additional time for setting of the glued end structures of the formed boxes before said boxes are discharged from the form blocks. It will be understood, however, that the kickoff control means can, if desired, be provided in connection with the outer raceway end member 93, or in any other desired part of the raceway structure. An illustrative form of kickoff control means, as shown more particularly in Fig. 7, comprises a cam block 96 which is affixed to the underside of the raceway end member 92. The sides of this cam block 96 converge upon its respective ends, and the flanges 94 of the raceway end member 92 are provided with outwardly bowed sections 97 which conformingly parallel the sides of said cam block 96, thus providing intermediate camming channels 98 through which the respective bell-crank arms and rollers of each form block are moved. As the bell-crank arms and rollers move through said camming channels, the same will be outswung, thus outswinging the kickoff levers 89 from the form block served thereby, whereby to remove the finished box from the latter (see Figs. 2, 3 and 7). As the bell-crank arms and rollers move away from the cam block 96, the same are immediately returned to normal inswing positions, so that the

kickoff levers 89 are withdrawn into the form block served thereby. This occurs well before the form block reaches a point in its circuit where it functions to take up a new box blank fed thereto.

Below the location of the kickoff control means, any suitable means may be provided for reception of the discharged finished boxes. For example, an endless conveyer belt 99 (see Figs. 2 and 3) may be utilized to receive and carry away discharged boxes to a desired collection point. The conveyer may be driven in any suitable manner, either from a moving shaft of the machine, or independently of the machine.

Either shaft 15 or shaft 16 of the endless chain assembly of form blocks may be utilized as a machine drive shaft, and power from a suitable source may be transmitted thereto by any convenient power transmission means.

From the above it will be understood that the present invention provides box making mechanism which is of the continuous motion type, and thus adapted to provide rapid and continuous output of finished boxes, and yet, due to the novel control of the box making material exercised by the mechanism, and especially by the novel endless chain assembly of form blocks 11, the production of boxes of accurate form, dimensions and symmetry is assured.

It will be understood that various changes could be made in the details of construction of the machine without departing from the scope of this invention defined by the following claims.

I claim:

1. In a machine of the character described, a multiplicity of form blocks, means to pivotally interconnect said form blocks one with another whereby to form an endless chain assembly thereof, means to support and drive said endless chain assembly of form blocks for continuous movement through a circulatory path defined by a straight outgoing course and a return course, said courses being connected at their ends by semi-circular courses leading from one to the other thereof, the pivotal connections between said form blocks being such that adjacent form blocks close together in box blank material gripping relation as they enter and move through said straight outgoing course but separate one from another when they move through a semi-circular course leading to said outgoing course, means to position box blanks for engagement by thus separated form blocks for deposit thereupon and over the sides thereof prior to movement of the latter into the outgoing straight course thereof, means contiguous to the ends of the form blocks, as they move in the straight outgoing course thereof, operative to infold and secure projecting end portions of the box blanks about the form block ends, means carried by the form blocks operative to discharge formed boxes from the form blocks when the latter are disposed in separated relation, and means located in the path of movement of said form blocks for actuating said discharge means.

2. In a machine of the character described, a multiplicity of form blocks, means to pivotally interconnect said form blocks one with another whereby to form an endless chain assembly thereof, means to support and drive said endless chain assembly of form blocks for continuous movement through a circulatory path defined by a straight outgoing course and a return course, said courses being connected at their ends by semi-circular courses leading from one to the

other thereof, the pivotal connections between said form blocks being such that adjacent form blocks close together in box blank material gripping relation as they enter and move through said straight outgoing course but separate one from another when they move through a semi-circular course leading to said outgoing course, means to position box blanks for engagement by thus separated form blocks for deposit thereupon and over the sides thereof prior to movement of the latter into the outgoing straight course thereof, means contiguous to the ends of the form blocks, as they move in the straight outgoing course thereof, operative to infold projecting end portions of the box blanks about the form block ends, means for applying glue to one of said end portions for adhering the same, when infolded, to other infolded end portions, and driven belts beyond said folding and glue applying means having courses thereof contiguous to sides of and moving with the straight outgoing course of the form blocks for retaining said end portions in infolded positions while the glue sets.

3. In a machine of the character described, a multiplicity of form blocks, means to pivotally interconnect said form blocks one with another whereby to form an endless chain assembly thereof, means to support and drive said endless chain assembly of form blocks for continuous movement through a circulatory path defined by a straight outgoing course and a return course, said courses being connected at their ends by semi-circular courses leading from one to the other thereof, the pivotal connections between said form blocks being such that adjacent form blocks close together in box blank material gripping relation as they enter and move through said straight outgoing course but separate one from another when they move through a semi-circular course leading to said outgoing course, means to position box blanks for engagement by thus separated form blocks for deposit thereupon and over the sides thereof prior to movement of the latter into the outgoing straight course thereof, means contiguous to the ends of the form blocks, as they move in the straight outgoing course thereof, operative to infold projecting end portions of the box blanks about the form block ends, means for applying glue to one of said end portions for adhering the same, when infolded, to other infolded end portions, means beyond said folding and glue applying means also contiguous to sides of the straight outgoing course of the form blocks for retaining said end portions in infolded positions while the glue sets, means carried by the form blocks operative to discharge formed boxes from the form blocks when the latter are disposed in separated relation, and means located in the path of movement of said form blocks for actuating said discharge means.

4. In a machine of the character described, a multiplicity of form blocks, means to pivotally interconnect said form blocks one with another whereby to form an endless chain assembly thereof, means to support and drive said endless chain assembly of form block for continuous movement through a circulatory path defined by a straight outgoing course and a straight return course, said courses being connected at their ends by semi-circular courses leading from one said straight course to the other, the pivotal connections between said form blocks being such that adjacent form blocks close together in box material gripping relation as they enter and move through said

straight courses but separate one from another when moving through said semi-circular courses, means to position box blanks for engagement by and deposit upon separated form blocks prior to movement of the latter into the straight outgoing course thereof, means contiguous to the ends of the form blocks, as they move in the straight outgoing course thereof, operative to infold projecting end portions of the box blanks about the form block ends, means for applying glue to one of said end portions for adhering the same, when infolded, to other infolded end portions, driven belts beyond said folding and glue applying means having courses thereof contiguous to sides of and moving with the straight outgoing course of the form blanks for retaining said end portions in folded condition while the glue is setting, and similar driven belts for like purpose contiguous to sides of and moving with the straight return course of the form blanks.

5. In a machine of the character described, a multiplicity of form blocks, means to pivotally interconnect said form blocks one with another whereby to form an endless chain assembly thereof, means to support and drive said endless chain assembly of form blocks for continuous movement through a circulatory path defined by a straight outgoing course and a straight return course, said courses being connected at their ends by semi-circular courses leading from one said straight course to the other, the pivotal connections between said form blocks being such that adjacent form blocks close together in box material gripping relation as they enter and move through said straight courses but separate one from another when moving through said semi-circular courses, means to position box blanks for engagement by and deposit upon separated form blocks prior to movement of the latter into the straight outgoing course thereof, means contiguous to the ends of the form blocks, as they move in the straight outgoing course thereof, operative to infold projecting end portions of the box blanks about the form block ends, means for applying glue to one of said end portions for adhering the same, when infolded, to other infolded end portions, driven belts beyond said folding and glue applying means having courses thereof contiguous to sides of and moving with the straight outgoing course of the form blanks for retaining said end portions in folded condition while the glue is setting, similar driven belts for like purpose contiguous to sides of and moving with the straight return course of the form blanks, means carried by the form blocks operative to discharge formed boxes from the form blocks as the latter separate upon movement out of the return straight course thereof, and means located in the path of movement of the form blocks for actuating said discharge means.

6. In a machine of the kind described, an endless chain assembly of form blocks, means to support and drive said assembly in a circulatory path defined by a straight outgoing course and a return course, a magazine for holding a stack of collapsed box blanks, and means opposed to opposite sides of the magazine for successively withdrawing box blanks from the magazine and opening and advancing the same to a position for engagement by and deposit on a form block approaching the straight outgoing course of form block movement, said means comprising pickup carrier devices each in the form of a horizontal body having an undercut wedge shaped forward tip portion, and means to move said devices

through a circular orbit in a plane substantially parallel to the plane of the blank to be withdrawn while maintaining the longitudinal axes of said devices perpendicular to the direction of blank withdrawing movement, said means to move said devices imparting thereto a composite movement including inward movement to engage the same with opposite ends of a collapsed bottom-most box blank in the magazine, advancing movement to withdraw the box blank from the magazine and to open and carry the same into position for engagement by a form block, and outward movement for withdrawing the same from the engaged box blank in time with the take-up of the latter by said form block.

7. In a machine of the kind described as defined in claim 6 including guide means extending between the magazine and the receiving end of the endless chain assembly of form blocks, said guide means being adapted to hold box blanks carried by the pickup carrier devices against displacement from aligned relation to the straight outgoing course of form block movement.

8. In a machine of the kind described as defined by claim 6 including guide means extending between the magazine and the receiving end of the endless chain assembly of form blocks, said guide means being adapted to hold box blanks carried by the pickup carrier devices against displacement from aligned relation to the straight outgoing course of form block movement, and means also extending between the magazine and the receiving end of the endless chain assembly of form blocks operative to hold down box blanks moved from the former to the latter against upward displacement.

9. In a machine of the kind described as defined in claim 6 wherein the tip portion of the body of each pickup carrier device is of narrowed width bounded by a longitudinally straight forward side edge and an outwardly and rearwardly inclined rearward side edge, and the body of the device back of said tip portion having a forwardly and downwardly inclined front face and a rearwardly and downwardly inclined back face.

10. In a machine of the kind described as defined in claim 6 wherein the tip portion of the body of each pickup carrier device is of narrowed width bounded by a longitudinally straight forward side edge and an outwardly and rearwardly inclined rearward side edge, the body of the device back of said tip portion having a forwardly and downwardly inclined front face and a rearwardly and downwardly inclined back face, and a box blank engaging clip mounted on the front face of the body.

11. In a machine of the kind described as defined in claim 6 wherein the tip portion of the body of each pickup carrier device is of narrowed width bounded by a longitudinally straight forward side edge and an outwardly and rearwardly inclined rearward side edge, the body of the device back of said tip portion having a forwardly and downwardly inclined front face and a rearwardly and downwardly inclined back face, and a forward and inwardly projecting folder blade mounted on the front face of the body.

12. In a device of the kind described as defined in claim 6 wherein the tip portion of the body of each pickup carrier device is of narrowed width bounded by a longitudinally straight forward side edge and an outwardly and rearwardly inclined rearward side edge, the body of the device back of said tip portion having a forwardly and down-

wardly inclined front face and a rearwardly and downwardly inclined back face, a box blank engaging clip mounted on the front face of the body, and a forwardly and inwardly projecting folder blade also mounted on the front face of the body.

13. In a machine of the character described, a multiplicity of form blocks, means to pivotally interconnect said form blocks one with another whereby to form an endless chain assembly thereof, means to support and drive said endless chain assembly of form blocks for continuous movement through a circulatory path defined by a straight outgoing course and a return course, said courses being connected at their ends by semi-circular courses leading from one to the other thereof, the pivotal connections between said form blocks being such that adjacent form blocks close together in box blank material gripping relation as they enter and move through said straight outgoing course but separate one from another when they move through a semi-circular course leading to said outgoing course, a magazine for holding a stack of longitudinally folded box blanks, driven turntables mounted adjacent to opposite sides of the magazine, pickup carriers having supporting shafts journaled in the turntables, each pickup carrier comprising a horizontal body having an undercut wedge shaped tip portion, and means to rotate said pickup carrier bodies about the axes of their shafts whereby to maintain the same perpendicular to the direction of movement of the straight outgoing course of form blocks, said pickup carrier bodies, as moved in circular orbit by the turntables, having a motion cycle comprising inward movement to enter the same in opposite ends of a bottommost folded box blank in the magazine so as to spread apart the folded portions thereof, advancing movement to withdraw said box blank from the magazine and carry the same into position for deposit on and over the sides of a separated form block about to enter the straight outgoing course of form block movement, and outward movement for withdrawing the same from the engaged box blank in time with the take-up of the latter by said form block.

14. In a machine of the kind described as defined in claim 13 including guide means extending between the magazine and the receiving end of the endless chain assembly of form blocks, said guide means being adapted to hold box blanks carried by the pickup carriers against displacement from aligned relation to the straight outgoing course of form block movement, and means also extending between the magazine and the receiving end of the endless chain assembly of form blocks operative to hold down box blanks moved from the former to the latter against upward displacement.

15. In a machine of the kind described as defined in claim 13 including means contiguous to the ends of the form blocks, as they move in the straight outgoing course thereof, operative to infold projecting end portions of box blanks about the form block ends, means for applying glue to one of said end portions for adhering the same, when infolded, to other infolded end portions, and means beyond said folding and glue applying means for retaining said end portions in infolded positions while the glue sets.

16. In a machine of the kind described as defined in claim 13 including means contiguous to the ends of the form blocks, as they move in the straight outgoing course thereof, operative to in-

fold projecting end portions of box blanks about the form block ends, means for applying glue to one of said end portions for adhering the same, when infolded, to other infolded end portions, driving belts beyond said folding and glue applying means having courses running contiguous to the ends of the form blocks, as moved through their straight courses, for retaining said end portions in infolded positions while the glue sets, means carried by the form blocks operative to discharge formed boxes from the form blocks when the latter are disposed in separated relation, and means located in the path of movement of said form blocks for actuating said discharge means.

17. In a machine of the kind described as defined in claim 13, wherein each form block is provided with means for discharging a formed box therefrom, said means comprising pivoted kickoff levers normally flush with the top of the form block, said levers having bell-crank arms projecting from the bottom of the form block, raceway means within and parallel to the circuit of the endless chain assembly of form blocks adapted to engage said bell-crank arms whereby to control the kickoff levers, and said raceway means including a cam block adapted to oscillate said bell-crank arms to effect discharge movement of the kickoff levers, said cam block being so located in the raceway means as to actuate the kickoff levers at a time when the form block is separated from its fellows.

18. In a machine of the kind described, an endless chain assembly of form blocks, means to sup-

port and drive said assembly in a circulatory path, and means opposed to a side of the magazine for successively withdrawing box blanks from the magazine and advancing the withdrawn blank for deposit on a form block, said means comprising a pickup carrier device formed by a horizontal body having an undercut wedge shaped forward tip portion, means to move said device through a circular orbit in plane substantially parallel to the plane of the blank to be withdrawn while maintaining the longitudinal axes of said device perpendicular to the direction of blank withdrawing movement, said means to move the device imparting thereto a composite movement including inward movement to engage the same with the blank to be withdrawn, advancing movement to withdraw the engaged blank and open and carry the same into position for engagement by a form block, and outward movement for withdrawing the same from the advanced blank in time with the take up of the latter by the form block.
